(57) **CLAIM**

The ornamental design for an air fryer, as shown and described.

DESCRIPTION

FIG. 1 is a front perspective view of an air fryer showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of encircled portion 9 shown in FIG. 2.

The dash-dash broken lines in the drawings depict the portions of the air fryer which form no part of the claimed design. The dot-dash broken lines illustrate the border of the enlarged detail views and form no part of the claimed design.
